GAS OPERATED GUN

Filed April 22, 1936

UNITED STATES PATENT OFFICE

2,101,862

GAS-OPERATED GUN

Stephen H. MacGregor, Savannah, Ga.

Application April 22, 1936, Serial No. 75,732

3 Claims. (Cl. 42—3)

(Granted under the Act of March 3, 1883, as amended April 30, 1928; 370 O. G. 757)

The invention described herein may be manufactured and used by or for the Government for governmental purposes, without the payment to me of any royalty thereon.

5 This invention relates to and is an improvement on gas-operated guns.

In guns of the gas-operated type, a piston movable by the gases of discharge is directly connected to an operating rod or actuator which by 10 its movement unlocks the breech bolt. The sudden blow imparted to this type of rod or actuator may result in damage and breakage of the rod or actuator and of the bolt locking mechanism. Furthermore, at the moment of unlocking and opening 15 of the breech the pressure therein is high. Extraction of the cartridge case under high pressure may be difficult, resulting in ruptured cartridge cases or torn extracting grooves.

The purpose of this invention is to provide a 20 delay action without loss of actuating power, and to apply the necessary power smoothly without violent or sudden contact of moving parts.

To these and other ends, the invention consists in the construction, arrangement and combination of elements described hereinafter and pointed out in the claims forming a part of this specification.

A practical embodiment of the invention is illustrated in the accompanying drawing, wherein:

30 Fig. 1 is a view in side elevation of a gun.

Fig. 2 is an enlarged view partly in side elevation and partly in section and showing the parts in the normal "action closed" position.

35 Fig. 3 is a similar view showing the parts at the start of the closing movement of the bolt from the full open position.

Fig. 4 is a transverse sectional view taken generally on the line 4—4 of Fig. 2 and showing the breech bolt in locked position.

40 Fig. 5 is a plan view of the front part of the breech bolt.

Fig. 6 is an enlarged view in side elevation of the handle piece of the breech-operating rod.

45 Fig. 7 is a sectional view on the line 7—7 of Fig. 6.

Referring to the drawing by characters of reference there is shown a gun barrel 5 threaded or otherwise secured in the front end of a receiver frame 6. A breech bolt 7 reciprocally mounted in 50 the receiver is formed with laterally extending wings, the left wing 8 having a pair of lugs 9—9 adapted, in breech-locking position, to enter recesses 10—10 in the receiver and the right wing 11, adapted, in breech-locking position, to enter 55 a slot 12 in the receiver, and having a cam mem-

ber 13 projecting beyond the side of the receiver. The bolt is unlocked by a rotary motion and during reciprocation the lugs 9—9 ride a guide way 14 while the right wing 11 rides over the upper edge of the corresponding side of the receiver.

A cylinder 15 carried by the barrel 5 underneath its front part receives a portion of the gases of discharge through a port 16 at the muzzle of the barrel. A hollow piston 17 working in the cylinder has an open rear end for receiving the front 10 part of a hollow rod 18 which in the normal position of rest of these elements has its front extremity spaced a slight distance from a plug 19 closing the front end of the piston. A helical spring 20 is confined between the plug 19 and a 15 seat 21 fixed in the hollow rod 18 by a pin 22. A helical spring 23 within the rod 18 is confined between the seat 21 and a follower rod 24 associated with the cartridge feeding mechanism.

The piston 17 has a collar 25 on its rear end for 20 engaging the rear edge of the cylinder 15 and limiting forward movement of the piston. The collar 25 is also arranged to engage a collar 26 on the rod 18 when the piston moves rearwardly and takes up the distance between its plug 19 and the 25 front end of the rod 18. The rod 18 is held in place by a latch 27 during the initial and independent rearward movement of the piston. The latch is carried by a stationary element, such as the stock 28, and is held by a spring 29 with its 30 end 30 normally in position to engage a lug 31 on the rod 18. The engagement between the latch end 30 and lug 31 is of a readily releasable type capable of being released when sufficient force is applied to the rod 18 during manual retracting 35 thereof.

An offset finger 32 on the rear end of the piston is arranged to trip the latch 27 when the collar 25 of the piston picks up the collar 26 of the rod. The rear end of the finger is provided with a 40 lug 33 adapted to engage the rear face of the collar 26. This provision is made so that when retraction is to be accomplished by manually acting on the rod 18 the piston will be carried along, (Fig. 2) and also for the purpose of limiting the 45 independent counterrecoil movement of the piston under the influence of its spring 20.

An offset handle piece 34 on the rear end of the rod 18 is disposed alongside the receiver and has a stud 35 riding in a guide groove 36 in the receiver. The handle piece is formed with a recess 37 having a front cam surface 38 and a rear cam surface 39. The projecting cam member 13 on the right wing of the breech bolt is disposed in the recess 37. When the rod 18 is moved rearwardly, 50 55

the front cam surface 38 raises the cam member 13 (Fig. 2) to rotate and unlock the bolt and then carry the bolt in recoil. When the rod 18 moves forwardly, the rear cam surface 39 engages the cam member 13 (Fig. 6) to move the bolt in counterrecoil and when the bolt arrives in battery the rod 18 continues its forward movement and lowers the cam member 13 to rotate the bolt into the locked position. With the bolt locked, the cam member 13 limits forward movement of the rod 18 under influence of its spring 23.

The handle piece 34 is provided with a handle 40 whereby the rod 18 is manually retracted to initially load a cartridge into the chamber of the gun barrel. During this operation the rod 18 and piston 17 move together by virtue of the coupling between the lug 33 on the finger 32 of the piston and the collar 26 on the rod 18. The force applied to manually retract the rod 18 causes the latch 27 to be disengaged from the lug 31.

When the gun is fired, a portion of the gases of discharge enters the cylinder 15 and drives the piston 17 rearwardly. Since the rod 18 is held by the latch 27, the initial and independent movement of the piston compresses the spring 20. When the piston has moved about three quarters of an inch it disengages the latch 27 from the rod 18 and picks up the rod which is driven rearwardly. The initial movement of the rod 18 unlocks the bolt 7, after which it is moved to the rear so that it may perform its usual functions as well understood in the art. The spring 23 which is energized during retraction of the rod restores the parts into battery, the cam member 13 of the bolt limiting forward movement of the rod 18 while the piston continues forward under the influence of its spring.

The piston takes the initial blow and insures a smooth movement of the rod 18 so that the parts will not be damaged or broken during the unlocking of the bolt 7.

I claim:

1. In a gun, a receiver, a barrel fixed to the receiver, a breech bolt reciprocable in the receiver, means whereby the bolt is locked to the

receiver, a cylinder fixed to the barrel, a gas passage between the barrel and cylinder, a piston in the cylinder, a collar on the rear end of the piston and engageable with the cylinder to limit forward movement of the piston, an offset finger 5 extending rearwardly from the piston, a bolt-operating rod having its front part slidable within the piston and adapted to be engaged and moved rearwardly by the piston, a spring seat in the rod, a driving spring for the rod, a spring between the 10 spring seat of the rod and the front end of the piston, a collar fixed on the rod and movable between the end of the piston and the end of the finger of the piston, a latch releasably engaging the rod to hold it against rearward movement, 15 said latch positioned so as to be tripped by the finger of the piston.

2. In a gun, a receiver, a barrel fixed to the receiver, a breech bolt reciprocable in the receiver, means whereby the bolt is locked to the receiver, a cylinder fixed to the barrel, a gas passage between the barrel and cylinder, a piston in the cylinder, a bolt-operating rod having its front part slidable within the piston, said piston and rod having a small relative movement before the 25 piston engages the rod to move it rearwardly, a spring seated on the rod and acting on the piston to hold it in advance of the rod, a driving spring for the rod, a latch releasably engaging the rod to hold it against rearward movement, and means whereby the piston controls the latch. 30

3. In a gun, a receiver, a barrel fixed to the receiver, a breech bolt reciprocable in the receiver, means whereby the bolt is locked to the receiver, a cylinder fixed to the barrel, a gas passage between the barrel and cylinder, a piston in the cylinder, a bolt-operating rod having its front part slid- 35 able within the piston, said piston and rod having a small relative movement before the piston engages the rod to move it rearwardly, a spring seated on the rod and acting on the piston to hold it in advance of the rod, and a driving spring for the rod. 40
